UNITED STATES PATENT OFFICE.

SAMUEL D. PALMER, OF ROCKFORD, ILLINOIS.

CHURN-COVER.

SPECIFICATION forming part of Letters Patent No. 530,602, dated December 11, 1894.

Application filed May 31, 1894. Serial No. 513,067. (No model.)

To all whom it may concern:

Be it known that I, SAMUEL D. PALMER, a citizen of the United States, residing at Rockford, in the county of Winnebago and State 5 of Illinois, have invented certain new and useful Improvements in Churn-Covers, of which the following is a specification.

The object of this invention is to construct a churn closure in which the center portion 10 is constructed of enameled metal, held in place by a metallic casing.

The further object of this invention is to hold a glass over an opening in the cover by the casing, and the further object of this invention is to form a detachable connection 15 between the center portion of the cover and the casing.

In the accompanying drawings, Figure 1, is an isometrical representation of the cover 20 showing its upper surface. Fig. 2, is an isometrical representation of the under face of the casing. Fig. 3, is an isometrical representation of the upper surface of the center portion. Fig. 4, is a vertical section through the 25 complete cover. Fig. 5, is an enlarged section of a portion of the center showing the opening for the glass.

In the construction of covers for churns the center portion is usually made from wood, 30 beveled by a metallic rim, and in such construction the wooden portion would by the action of moisture and heat soon crack and split, and these crevices in the wood form receptacles for the lodgment of particles of cream, which soon become rancid, and soon render the cover useless, and it is these disadvantages that I seek to overcome by my improved construction of cover.

The center portion 1, of the cover is constructed from sheet metal having a rim 2, at 40 its outer edge and from which extends a flange 3, lying in the same plane as the main portion. To the center of the center portion and to its upper face is riveted a catch composed 45 of ears 4, vertical edges 5, and a horizontal top 6, having a portion 7, cut away. To one side of the center is riveted a hook by its base 8 its free end being provided with a lengthwise slot 9, and in close proximity to 50 this hook is a hole, or opening 10, and holes

11, are formed in the flange 3. A bead 12, is formed around the opening 10, some distance from its edge. This center portion after being constructed in the manner described is subjected to the enameling process which will 55 fill in around the catch and hook forming a smooth and non-corrosive surface.

An outer casing is composed of a ring 13, having a depending rim 14. The ring has a central brace 15, spanning the open space and 60 from the center of the brace rises a boss 16, having a square central opening 17. The under face of the central portion of the brace is provided with a recess 18, to receive the catch secured to the upper face of the center, and 65 has a portion 19, cut away as shown at Fig. 1. A circular recess 20, is formed in the enlarged portion of the brace and in the bottom of this recess is formed a square recess 21, which is provided with a circular opening 22, of a 70 diameter equal to the circular opening 10, in the enameled center portion. A recess 23, is also formed in the under face of the brace which receives the hook 8. Screw threaded holes 24, are formed in the ring 13, at the 75 point of connection of the brace.

In securing the parts of the cover together a suitable packing is placed around the opening 10, in the enameled center, and within the square recess 21, in the under face of the 80 brace is placed a square of glass 25, and a bolt 26, is placed within the slotted end of the hook 8. The outer casing is then placed over the enameled center, the bolt passing upward through the perforated boss 27, receiving a nut on its upper end firmly clamping the brace and enameled center together at 85 this point. In center in the casing in its connection with the center, the catch will enter the recess 18, in the under face of the brace, 90 and the head of the bolt 28, is passed through the opening 19, in the upper face of the brace and central boss 16, the square portion of the bolt near its head entering the square opening in the boss. A nut 29, placed upon the bolt 95 and turned down against the upper surface of the boss will form a connection between the catch and brace, the opening in the catch permitting the entrance of the shank portion of the bolt. Screws 30, are passed through 100

holes 11, in the flange into the threaded holes 24 in the casing forming a connection between the center and casing.

In placing the casing in position over the 5 enameled center the glass 25, will be firmly embedded in the packing laid around the circular opening 10, in the center.

Between the pepending rim 14, of the casing and the rim 2, of the enameled center 10 when the parts are joined as herein described will be formed an annular recess, within which is seated a suitable packing ring 31, and is held in place by its pressure against the rims which form a seat for the end of the churn 15 or other device for forming a water tight joint between the cover and churn body. The depression 32, formed in the under face of the brace receives the heads of the rivets, securing the catch and hook to the enameled center. 20 To the screw threaded end of the bolt 28, may be attached the devices acting in conjunction with other devices having a connection with the churn body for holding the cover in its connection with the churn body, and 25 may be any of the various devices employed for that purpose.

In the employment of the enameled center it is necessary that all independent parts having a connection therewith should be riveted 30 thereto and be composed of metal which will expand and contract uniformly with the center in order to avoid cracking of the enamel, and after it has been enameled it will not stand very rough usage. By this construction 35 the glass will be held firmly in position, and the opening will be perfectly sealed, preventing leaking at this point.

I claim as my invention—

1. A cover for a churn consisting of a center, a metallic casing surrounding the center, having a brace integral therewith and overlying the center, a projection secured to the upper face of the center and means slidably connecting the projection with the brace.

45 2. A cover for a churn consisting of a center, a metallic casing surrounding the center having a brace integral therewith and overlying the center, a catch secured to the upper surface of the center, and a bolt slidably connecting the catch and brace.

3. A cover for a churn consisting of a center, a metallic casing surrounding the center having a brace integral therewith and overlying the center, the brace having a recess in 55 its under face, a catch secured to the upper

face of the center and located in the recess of the brace and means connecting the catch and brace.

4. A cover for a churn consisting of a center, a metallic casing surrounding the center 60 having a brace integral therewith and overlying the center, the brace having a recess in its under face, a catch secured to the upper face of the center and located in the recess of the brace, a bolt engaging the catch, a nut 65 located on the bolt clamping the catch to the brace.

5. A cover for a churn, consisting of a center, a casing having a brace, a catch secured to the center, a recess in the under face of 70 the brace receiving the catch, the upper surface of the brace supporting a boss having a portion of one face cut away, a bolt connecting the center and brace, the head of the bolt adapted to pass under the catch through the 75 cut away portion.

6. A cover for a churn, consisting of a center, a metallic casing surrounding the center having a projection extending inward therefrom and integral therewith, a glass located 80 between the projection and center, a hook secured to the upper face of the center and means connecting the hook and projection.

7. A cover for a churn consisting of a center, a metallic casing surrounding the center 85 having a projection extending inward therefrom and integral therewith, a glass located between the projection and center, a hook secured to the upper face of the center and means connecting the hook and projection. 90

8. A cover for a churn consisting of a center, a metallic casing surrounding the center having a projection extending inward therefrom and integral therewith and overlying the center, a glass located between the projection and center means connecting the projection and center, and a bead formed in the center around the glass opening receiving a packing or cement.

9. A cover for a churn, consisting of a center and a casing connected thereto, a brace connected to the casing having a recess in its under face, a glass placed within the recess, an opening in the brace and an opening in the center coinciding, one opening located 105 over the glass and the other beneath it.

SAMUEL D. PALMER.
